US00D973911S

(12) United States Design Patent (10) Patent No.: US D973,911 S
Behere et al. (45) Date of Patent: * Dec. 27, 2022

(54) CRITICAL CARE SUITE

(71) Applicant: KONINKLIJKE PHILIPS N.V.,
Eindhoven (NL)

(72) Inventors: Sachin Suresh Behere, Singapore (SG);
Nigel Geh Keong Teck, Singapore (SG)

(73) Assignee: KONINKLIJKE PHILIPS N.V.,
Eindhoven (NL)

() Term: 15 Years

(21) Appl. No.: 29/712,457

(22) Filed: Nov. 8, 2019

(30) Foreign Application Priority Data

May 8, 2019 (EM) 006431714

(51) LOC (13) Cl. 25-02

(52) U.S. Cl.

USPC D25/58; D6/332; D6/673; D25/31

(58) Field of Classification Search

USPC D25/1, 3-35, 58; D6/640-644, 332, 677,
D6/718.14, 672, 336, 664, 673; D24/185;

D16/215; D20/10

CPC E04H 1/00-12; E04H 1/1205-1277; E04H
1/14; E04H 2001/1294
